(57) CLAIM

I claim the ornamental design for a chaise lounge, as shown and described.

DESCRIPTION

FIG. 1 is a perspective view of my chaise lounge;

FIG. 2 is a front view thereof;

FIG. 3 is a right side view thereof;

FIG. 4 is a left side view thereof;

FIG. 5 is a top view thereof;

FIG. 6 is a rear view thereof; and,

FIG. 7 is a close-up view of a leg of my chaise lounge. The leg is shown separately for ease of illustration.
